F. P. MICHEL, OF ROCHESTER, NEW YORK.

Letters Patent No. 76,938, dated April 21, 1868; antedated April 14, 1868.

IMPROVEMENT IN PUMP-PISTONS.

The Schedule referred to in these Letters Patent and making part of the same.

TO ALL WHOM IT MAY CONCERN:

Be it known that I, F. P. MICHEL, of Rochester, in the county of Monroe, and State of New York, have invented a certain new and useful Improvement in Pumps; and I do hereby declare that the following is a full and exact description thereof, reference being had to the accompanying drawings, making part of this specification.

Figure 1 is a central vertical section of my improved pump.

Figure 2, a perspective view of the piston, with a portion broken away to show the interior arrangement.

Figures 3 and 4, perspective views of the valves.

Like letters of reference indicate corresponding parts in all the figures.

This improvement belongs to that class of double-acting pumps in which the water enters alternately at the top and bottom of the piston, and is elevated through the hollow piston-rod. The invention consists in the construction and arrangement of the piston, which is cast entirely hollow, with ribs on the sides, and a double-shouldered hook on the removable bottom-plate, which ribs and hooks serve to stop the valves that cover and uncover the ports.

As represented in the drawings, A is the piston, which plays in the ordinary cylinder having a side passage, and B is the hollow piston-rod, extending to the top of the well.

The piston is composed of two principal parts, a rim, a, with solid head, b, and a removable plate, c, at the bottom, which is attached by bolts or equivalent. These parts are respectively provided with ports, d d, d' d', as shown. The inside of the rim of the piston is provided on one side with a suitable number of ribs, or lugs, f f, leaving an open space at the top and bottom. The removable bottom of the piston is also provided with a hook, h, projecting upward from the centre, and provided with double shoulders, i i, corresponding in position with the ends g g' of the ribs.

The valves consist simply of two thin, plain disks, C C', having holes, k k, in the centre, for the passage of the water. The valve C is introduced in place in the upper part of the piston by simply inserting it from the bottom over the tops of the ribs f, which are on one side only of the rim. The valve C' is then hooked over the hook h, and the plate c is attached in place to the rim a. Thus arranged, it will be seen that both valves rest square upon the ends of the ribs and the hook, and play between them and the heads of the piston.

The great value of this invention consists in casting the piston entirely hollow, and providing it only with the ribs and hook f h, to retain the valves. These parts are simply cast on, and require but very little fitting. The ribs, by being situated on only one side of the rim, allow an easy insertion of the upper valve, and the hook allows an easy application of the lower valve, and when the piston is closed, the valves are retained in place perfectly. This ready inserting and removing of the valves is of much importance.

By this construction, also, a great advantage is attained in making the space between the two valves entirely open and unobstructed, so that no mud or extraneous matter can collect to obstruct the parts. Much difficulty is experienced in this respect in ordinary pistons, the space in which is contracted and tortuous.

I am aware that a plain disk-valve has been used in a piston; covering and uncovering the ports. Such I do not claim. My invention consists only in the special arrangement of the ribs and hook with the hollow piston, whereby the valves are easily inserted and removed, and a free passage is attained for the water. Such a device, so far as I am aware, is entirely new.

What I claim as my invention, and desire to secure by Letters Patent, is—

The construction of the hollow piston A, with the ribs f f, and hook h, for the ready insertion and removal of the valves, the whole arranged and operating in the manner and for the purpose specified.

In witness whereof, I have hereunto signed my name in the presence of two subscribing witnesses.

F. P. MICHEL
